UNITED STATES PATENT OFFICE.

HARRY LONGACRE, OF BROOKLYN, NEW YORK.

TOBACCO PIPE.

Application filed May 2, 1921. Serial No. 466,075.

To all whom it may concern:

Be it known that I, HARRY LONGACRE, a citizen of the United States, and resident of Brooklyn, in the county of Kings and 5 State of New York, have invented certain new and useful Improvements in Tobacco Pipes, of which the following is a full, clear, and exact specification.

This invention relates to tobacco pipes 10 and has for its objects to provide a pipe in the form of a cigar which may be readily cleaned when required and which is so constructed as to prevent saliva from reaching the bowl or stopping up the passage 15 between the latter and the mouth-piece. Other objects will appear as the description proceeds.

The invention will be first hereinafter described in connection with the accompanying 20 drawings, which constitute part of this specification, and then more specifically defined in the claim at the end of the description.

In the accompanying drawings, wherein 25 similar reference characters are used to designate corresponding parts throughout the several views:

Figure 1 is a side elevation of a cigar-shaped pipe constructed substantially in accordance with this invention.

Figure 2 is a longitudinal section of said pipe.

Figure 3 is a detailed side elevation of the bowl portion of the pipe.

Figure 4 is an end elevation looking at the right hand end of the part shown in Figure 3.

Figure 5 is a longitudinal section of the middle section or stem portion of the pipe, 40 and

Figure 6 is a longitudinal section of the mouth-piece or section.

The pipe comprises a bowl section 1, a stem section 2, and a mouth-piece or section 3 which are detachably connected end to end, as best shown in Figure 2. When so connected, the bowl section 1 abuts against one end of the stem section 2 at 15, while the other end of said stem section 50 abuts against the mouth-piece at 19. The bowl section 1 has a reduced externally screw threaded extension 13 detachably engaging an internally screw threaded end portion 14 on the stem section 2, while the 55 other end of said stem section has a reduced externally screw threaded extension

18 detachably engaging an internally threaded end portion 20 of the mouth-piece 3. It will thus be seen that the three sections of the pipe may be readily taken 60 apart for cleaning whenever required.

The stem section 2 has an enlarged cavity 17 into which a cylindrical projecting lug 5 on the bowl section 1 fits when said sections are assembled. The cylindrical lug 65 5 has a spiral groove 7 formed in its surface and extending from one end to the other. Said groove communicates at one end with a longitudinal passage 6 leading to the bowl 4 into which the tobacco is 70 placed for smoking in the usual way. At the other end the spiral groove 7 terminates in a central opening 8 which registers with a longitudinal passage 9 in the adjacent end of the stem section 2. The mouth-piece 3 has a longitudinal passage 11 leading to an enlarged cavity or chamber 10 which communicates with the passage 9 in the stem section when the parts are assembled. The stem section is also provided 75 with the usual bead 12 at its end, and the exterior of the pipe as a whole may be suitably marked to resemble the ordinary wrapping and band of a cigar, as shown in Figure 1.

When the pipe is in use, smoke is drawn from the bowl 4 through the passage 6, spiral groove 7, passage 9, chamber 10, and passage 11 into the mouth of the smoker. Any saliva which may find its way through said 90 passage 11 will lodge in said chamber 10 which is large enough to prevent the clogging of the passage 9 thereby.

I claim:

In a tobacco pipe, the combination with 95 a bowl section having an integral reduced extension provided with a spiral groove on its surface communicating at one end with the bowl, of a stem section having a cavity to fit around said grooved extension of the bowl section and detachably connected to said section, and a separate mouth-piece having a passage therethrough, the inner end of said passage in the mouth-piece being enlarged to form a saliva chamber, and 100 the outer edge of said chamber being internally threaded to detachably engage over the stem section.

In testimony whereof I have signed my 105 name to this specification.

HARRY LONGACRE.
